WIRE GRINDING MACHINE

Carl A. Carlson, Worcester, Mass., assignor to
 Norton Company, Worcester, Mass., a corpora-
 tion of Massachusetts

Application July 15, 1944, Serial No. 545,121

11 Claims. (Cl. 51—90)

This invention relates to grinding machines, and more particularly to a machine for grinding wire or other similar work pieces.

One object of the invention is to provide a simple and thoroughly practical grinding machine for grinding continuous work pieces such as wire and the like. A further object of the invention is to provide a wire grinding machine having opposed rotatable grinding wheels which are revolved while the work piece to be ground is fed therebetween.

A further object of the invention is to provide a wire grinding machine having a rotatable frame which supports a pair of opposed grinding wheels, in which the rotatable support and the grinding wheels are independently driven. A further object of the invention is to provide a wire grinding machine having a pair of opposed revolvable grinding wheels which are adjustably supported and provided with feeding mechanisms whereby the grinding wheels may be fed toward and from the axis of revolution during a grinding operation. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings in which is illustrated one of many possible embodiments of the mechanical features of this invention,

Fig. 1 is a cross sectional view, taken approximately on the line 1—1 of Fig. 4, showing the arrangement of the grinding wheels and the rotatable support therefor;

Fig. 2 is a fragmentary elevation, on an enlarged scale, of one of the grinding wheel units;

Fig. 3 is a fragmentary sectional view, on an enlarged scale, of the feeding mechanism for the grinding wheel unit shown in Fig. 2;

Fig. 4 is a longitudinal sectional view, taken approximately on the line 4—4 of Fig. 1;

Fig. 5 is a fragmentary horizontal sectional view, on an enlarged scale, taken approximately on the line 5—5 of Fig. 7, showing the plunger mechanism for actuating the wheel feed;

Fig. 6 is a diagrammatic plan view of the machine, showing the wire reeling and supporting mechanism together with the drive for the revolvable wheel unit;

Fig. 7 is a fragmentary front elevation of the improved wire grinding machine;

Fig. 8 is a fragmentary diagrammatic view, on

an enlarged scale, showing the relationship of the grinding wheels and the work steadyng guide; and

Fig. 9 is a fragmentary detail view, showing the support for the work steadyng guide.

A wire grinding machine has been shown in the drawings having a base 10 which supports a pair of upwardly extending brackets 11 and 12 which serve as rotatable support for a pair of spaced rotatable trunnions 13 and 14. The trunnions 13 and 14 are formed integral with a revolvable wheel supporting drum 15 which is preferably formed by providing spaced plates 16, 17 and 18 which are interconnected by longitudinally extending members 19, 20, 21, 22, 23 and 24. The end plates 16 and 18 are either formed integral with or fixedly mounted relative to the trunnions 13 and 14, respectively.

A wire supporting reel 25 is rotatably supported to carry a coil of wire 26 to be ground which is fed through a central aperture 27 in the trunnion 13 and passes through the center of the rotatable wheel support 15 and through a central aperture 28 formed within the trunnion 14. The ground wire is reeled up on a motor driven reel 29 which is supported adjacent to the right-hand end of the machine. The motor for driving the reel 29 is preferably a variable speed motor which may be manually controlled so as to vary the rate of feed of the wire 26 through the machine.

A driving mechanism is provided for rotatting the wheel supporting drum 15 comprising a variable speed electric motor 30 which is provided with a multi-V-groove pulley 31. The pulley 31 is connected by multiple V-belts 32 with a large diameter multi-V-groove pulley 33 which is mounted on the left-hand end of the trunnion 13. By varying the speed of the motor 30, the rotatable wheel supporting drum may be rotated at the desired speed for the grinding operation.

The rotatable drum 15 serves as a support for a pair of opposed grinding wheels 35 and 36 which are arranged to engage the wire 26 to be ground on diametrically opposite sides. Each of the grinding wheels 35 and 36 is preferably independently rotated by independent variable speed motors so that the speed of rotation of the wheels may be adjusted to produce the desired grinding action. Each of the grinding wheels is preferably supported on a movable member so that the wheel may be adjusted toward and from the wire to be ground so as to compensate for wheel wear and also to produce the desired feeding action. In the preferred construction, the grinding wheel 36 is supported on a pivotally mounted frame 37

which is supported by a pair of spaced opposed pivot screws 38 and 39. An electric motor 40 is adjustably supported on the wheel support 37 and is connected by a multiple V-belt 41 with a pulley 42 on the left-hand end of a wheel spindle 43 which supports the grinding wheel 36. A manually adjustable screw 44 is provided by means of which the motor 40 may be adjusted on the wheel support 37 so as to properly tension the driving belts 41.

A similar wheel support 45 is provided for the grinding wheel 35. The wheel support 45 is pivotally supported by a pair of spaced opposed pivot screws 46 and 47. An electric motor 48 is adjustably mounted on the wheel support 45 and is connected by a multiple V-belt 49 with a pulley 50 which is supported on the left-hand end of a wheel spindle 51 which rotatably supports the grinding wheel 35. A manually adjustable screw 52 is provided for adjusting the motor 48 relative to the support 45 to facilitate tensioning the driving belts 49 as desired.

Each of the wheel supports 37 and 45 is provided with a feeding mechanism whereby the grinding wheels 36 and 35 respectively may be fed or adjusted toward and from the axis of rotation of the drum 15. These mechanisms are substantially identical, consequently only one will be described in detail. A feed screw 55 is pivotally connected by a stud 56 to a slide block 57 which is slidably supported on the wheel support 37. The feed screw 55 meshes with or engages a nut 58 which is rotatably supported in a portion 59 formed integral with or fixedly mounted relative to the drum 15. The nut 58 is provided with an outwardly extending integral flange 60 which has a gear 61 formed on its periphery meshing with a gear 62. The gear 62 is fixedly supported on a rotatable stud 63. The stud 63 also supports a gear 64 which is keyed thereto. The gear 64 meshes with a gear 65 which is formed integral with a rotatable sleeve 66 having a central clearance aperture 67 within which the feed screw 55 may telescope. A gear 68 is mounted at the lower end of the sleeve 66 and meshes with a gear 69 which is supported on a rotatable shaft 70. A star wheel 71 is fixedly mounted on the outer end of the shaft 70. It will be readily apparent that rotary motion of the star wheel 71 will be transmitted through the gear 69, the gear 68, the sleeve 66, the gear 65, the gear 64, the gear 62, and the gear 61, to rotate the nut 58 relative to the non-rotatable screw 55 so as to cause the screw 55 to move in an axial direction so as to feed the grinding wheel 36 either toward or from the axis of the rotatable support 15.

Only one pair of opposed grinding wheels has been illustrated in the drawings but it will be readily apparent that, if desired, a plurality of pairs of opposed grinding wheels may be readily provided by lengthening the machine so as to provide sufficient support for the same on the rotatable drum 15.

In order to provide a controlled feeding movement of the grinding wheel 36 during rotation of the drum 15, a pair of spring-pressed plungers 75 and 76 are provided which are arranged to be thrown into the path of the star wheel 71. When it is desired to initiate a feeding movement of the grinding wheel 36, the plunger 75 is moved toward the right (Fig. 5) into an operative position in the path of the star wheel 71. When the drum 15 is rotated, the star wheel 71 moves past the plunger 75, the stationary plunger

75 will impart a partial rotation to the star wheel 71 and thus transmit a feeding movement through the mechanism above described so as to adjust the grinding wheel 36 either toward or from the axis of the drum 15. Similarly, if the plunger 76 is moved into an operative position 76a, as shown in dotted lines in Fig. 5, the revolving star wheel 71 engaging the plunger 76 will impart a rotary motion to the star wheel 71 in the opposite direction which will transmit a feeding movement to the grinding wheel 36, also in the opposite direction. A pair of actuating knobs 77 and 78 are provided for actuating the plungers 75 and 76, respectively.

It is desirable that only one of the plungers be moved into an operating position while the other plunger is maintained in an inoperative position. This is preferably accomplished by providing an inter-connection between the two plungers. A bracket 79 is fixedly mounted on a casing 80 which surrounds the machine. A rock arm 81 is pivotally supported by a stud 82 on the bracket 79. The rock arm 81 is connected by studs 83 and 84 with the plungers 75 and 76, respectively. It will be readily apparent from the foregoing disclosure that when the plunger or stud 75 is moved into an operative position by manual actuation of the knob 77, the plunger 76 will be moved in the opposite direction and maintained in an inoperative position. Similarly, when the plunger 76 is moved into an operative position, the plunger 75 will be maintained in an inoperative position. Balanced compression springs are associated with each of the plungers 75 and 76 normally to maintain them in an inoperative position.

A pair of similar plungers 85 and 86 are provided on the opposite side of the casing 80 which are arranged to be moved into the path of opposite sides of the star wheel 73 as it revolves with the drum 15. The plungers 85 and 86 are interconnected by means of a rock arm 87 so that only one of the plungers 85 or 86 may be moved into an operative position while the other plunger is maintained inoperative. Actuating knobs 88 and 89 are provided for actuating the plungers 85 and 86, respectively. It will be readily apparent from the foregoing disclosure that by actuating the plungers 76 or 75 on one side of the frame 80, the grinding wheel 36 may be fed either toward or from the wire to be ground and similarly by actuation of the plungers 85 and 86 on the opposite side of the casing, the grinding wheel 35 may be adjusted either toward or from the axis of the wire to be ground during rotation of the drum 15.

The wire 26, after it leaves the reel 25, passes through a pair of opposed guiding surfaces 90 and 91 which are preferably adjustable relatively toward and from each other so that the wire passing through the drum 15 may be maintained under proper tension. As the wire 26 passes from the other end of the machine, it passes under a dial indicator 92 which visibly indicates the size of the finish ground wire. By observing the dial indicator, the operator may readily observe whether or not the wire is being ground to size and make suitable feeding adjustments of the wheels to compensate for any deviations in wire size.

In order to drive the grinding wheels 35 and 36 independently, a plurality of slip rings 94 are provided adjacent to the right-hand end of the trunnion 14. A main starter switch 95 is provided for opening and closing the circuit to

supply power through independent switches 96 and 97 which are connected through slip rings 94 to control the electric current passing to the motors 40 and 48, respectively.

It is desirable to steady the wire being ground between the grinding wheels 35 and 36 by means of a work steadyng guide bar 100 which is fixedly supported on a bar 101. The bar 101 is keyed to the plates 16 and 17, as indicated in Fig. 9. The grinding wheels 35 and 36 are preferably rotated in opposite directions, that is, so that at the point of grinding contact with the wire being ground, the thrust of the grinding wheels will be in a direction so as to hold the wire against the work supporting guide 100 so that the wire will be rigidly supported as it is ground away.

The operation of the improved wire grinding machine will be readily apparent from the foregoing disclosure. A reel of wire 26 to be ground is supported on the rotatable reel 25. The wire 26 is passed through the tension guides 90 and 91 and is threaded through the central apertures in the trunnions 13 and 14, respectively, through a guiding surface 93 which is located below the dial gauge 92, and onto the motor driven wind-up reel 28. The motor 30 may then be started to rotate the drum 15, and the motors 40 and 48 started to rotate the grinding wheels 36 and 35, respectively. The wheels 36 and 35 may then be fed toward the periphery of the wire to be ground to the desired extent, after which the motor driven reel 29 may be started to draw the wire 26 through the machine while the grinding wheels 36 and 35 rotate and revolve about its peripheral surface to grind the same to the desired and predetermined extent. As above described, either of the wheels 36 or 35 may be adjusted by manipulation of the independent feeding mechanisms. The speed of revolution of the drum 15, the speed of rotation of the grinding wheels 36 and 35, and the speed of rotation of the wind-up reel 29 may be independently adjusted as desired so as to produce the desired and predetermined grinding action upon the surface of the wire 26 to be ground.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a wire grinding machine having a base, a rotatable frame, a trunnion at each end of said frame, a pair of spaced journal bearings on said base rotatably to support said trunnions and frame, a central aperture through said trunnions and frame for guiding wire to be ground therethrough, means to rotate said frame, a pair of opposed rotatable grinding wheels within said frame, an adjustable support on said frame for each of said wheels, an independent electric motor on each of said supports for rotating each of said grinding wheels, and independent means for independently adjusting each of said supports relative to said frame to feed the grinding wheels either toward or from the wire to be ground.

2. In a wire grinding machine having a base, a rotatable frame, a trunnion at each end of said

frame, a pair of spaced journal bearings on said base rotatably to support said trunnions and frame, a central aperture through said trunnions and frame for guiding wire to be ground therethrough, means to rotate said frame, a rotatable grinding wheel on said frame, an adjustable support on said frame for said wheel, an electric motor on said support for rotating said grinding wheel, a work steadyng guide on said frame, a nut and screw mechanism for adjusting said support relative to said frame to feed the grinding wheel either toward or from the wire to be ground, and means including a star wheel mechanism to facilitate automatically adjusting the position of said grinding wheel while said frame is rotating.

3. In a wire grinding machine having a base, a rotatable frame, a trunnion at each end of said frame, a pair of spaced journal bearings on said base rotatably to support said trunnion and frame, a central aperture through said trunnions and frame for guiding wire to be ground therethrough, means to rotate said frame, a pair of opposed rotatable grinding wheels supported within said frame, an adjustable support on said frame for each of said wheels, an independent driving motor on each of said supports for independently rotating each of said wheels in opposite directions, a work steadyng guide between said wheels to steady the wire during grinding, and an independent nut and screw mechanism for adjusting each of said supports relative to said frame to feed said wheels either toward or from the wire to be ground.

4. In a wire grinding machine having a base, a rotatable frame, a trunnion at each end of said frame, a pair of spaced journal bearings on said base rotatably to support said trunnions and frame, a central aperture through said trunnions and frame for guiding wire to be ground therethrough, means to rotate said frame, a pair of opposed rotatable grinding wheels supported within said frame, a pivotally mounted support on said frame for each of said grinding wheels, an independent driving motor on each of said supports for independently rotating each of said wheels in opposite directions, a work steadyng guide on said frame which projects between said wheels to steady the wire being ground, and an independent nut and screw mechanism for independently swinging said supports relative to said frame to feed said grinding wheels either toward or from the wire to be ground.

5. In a wire grinding machine having a base, a rotatable frame, a trunnion at each end of said frame, a pair of spaced journal bearings on said base rotatably to support said trunnions and frame, a central aperture through said trunnions and frame for guiding wire to be ground therethrough, means to rotate said frame, a pair of opposed rotatable grinding wheels supported within said frame, a pivotally mounted support on said frame for each of said grinding wheels, an independent driving motor on each of said supports for independently rotating each of said wheels, an independent nut and screw mechanism for independently swinging said supports relative to said frame to feed said grinding wheels either toward or from the wire to be ground, and means including a star wheel mechanism automatically to adjust said screws during rotation of said frame.

6. In a wire grinding machine having a base, a rotatable frame, a trunnion at each end of said frame, a pair of spaced journal bearings on said base rotatably to support said trunnions and

frame, a central aperture through said trunnions and frame for guiding wire to be ground therethrough, means to rotate said frame, a pair of opposed rotatable grinding wheels supported within said frame, a pivotally mounted support on said frame for each of said grinding wheels, said pivot for the supports being adjacent to the periphery of said frame, an independent driving motor on each of said supports for independently rotating each of said wheels, and means including a nut and screw mechanism for swinging each of said supports about its pivot to feed said grinding wheels either toward or from the wire to be ground.

7. In a wire grinding machine having a base, a rotatable frame, a pair of trunnions at each end of said frame, a pair of spaced journal bearings on said base rotatably to support said trunnions and frame, a central aperture through said trunnions and frame for guiding wire to be ground therethrough, means to rotate said frame, a pair of opposed rotatable grinding wheels supported on said frame, an independent pivotally mounted support on said frame for each of said wheels, said pivotal supports being arranged so that the grinding wheel axes swing along a path substantially diametrically of said frame, an independent motor on each of said supports for independently rotating said wheels, an independent nut and screw mechanism for adjusting each of said supports relative to said frame to feed said grinding wheels either toward or from the wire to be ground, a star wheel operatively connected to rotate each of said feed screws, and a normally inoperative plunger which is arranged to be manually moved into operative position in the path of said star wheel as it revolves to facilitate adjustment of the position of the grinding wheels.

8. In a wire grinding machine having a base, a rotatable frame, a pair of trunnions at each end of said frame, a pair of spaced journal bearings on said base rotatably to support said trunnions and frame, a central aperture through said trunnions and frame for guiding wire to be ground therethrough, means to rotate said frame, a pair of opposed rotatable grinding wheels supported on said frame, an independent pivotally mounted support on said frame for each of said wheels, said pivotal supports being arranged so that the grinding wheel axes swing along a path substantially diametrically of said frame, an independent motor on each of said supports for independently rotating said wheels, an independent nut and screw mechanism for adjusting each of said supports relative to said frame to feed said grinding wheels either toward or from the wire to be ground, a star wheel operatively connected to rotate each of said feed screws, and a pair of normally inoperative spaced plungers which are arranged to be moved into the path of said star wheel at diametrically opposite positions to facilitate adjustment of said grinding wheel either toward or from the wire to be ground.

9. In a wire grinding machine having a base, a rotatable frame, a pair of trunnions at each end of said frame, a pair of spaced journal bearings on said base rotatably to support said trunnions and frame, a central aperture through said trunnions and frame for guiding wire to be ground therethrough, means to rotate said frame, a pair of opposed rotatable grinding wheels supported on said frame, an independent pivotally

mounted support on said frame for each of said wheels, said pivotal supports being arranged so that the grinding wheel axes swing along a path substantially diametrically of said frame, an independent motor on each of said supports for independently rotating said wheels, an independent nut and screw mechanism for adjusting each of said supports relative to said frame to feed said grinding wheels either toward or from the wire to be ground, a star wheel operatively connected to rotate each of said feed screws, a pair of normally inoperative plungers which are arranged to be moved into the path of said star wheels at diametrically opposite positions to facilitate adjustment of said grinding wheel either toward or from the work axis, and interconnections between said plunger whereby only one of said plungers may be rendered operative while the other is maintained in an inoperative position.

10. In a wire grinding machine having a base, a rotatable frame, a pair of trunnions at each end of said frame, a pair of spaced journal bearings on said base rotatably to support said trunnions and frame, a central aperture through said trunnions and frame for guiding wire to be ground therethrough, means to rotate said frame, a pair of opposed rotatable grinding wheels supported on said frame, an independent pivotally mounted support on said frame for each of said wheels, said pivotal supports being arranged so that the grinding wheel axes swing along a path substantially diametrically of said frame, an independent motor on each of said supports for independently rotating said wheels, an independent nut and screw mechanism for adjusting each of said supports relative to said frame to feed said grinding wheels either toward or from the wire to be ground, a star wheel operatively connected to rotate each of said feed screws, and a normally inoperative plunger associated with each of said feed screws which is arranged to be moved into the path of said star wheels as they revolve independently to adjust the position of each of said grinding wheels.

11. In a wire grinding machine having a base, a rotatable frame, a pair of trunnions at each end of said frame, a pair of spaced journal bearings on said base rotatably to support said trunnions and frame, a central aperture through said trunnions and frame for guiding wire to be ground therethrough, means to rotate said frame, a pair of opposed rotatable grinding wheels supported on said frame, an independent pivotally mounted support on said frame for each of said wheels, said pivotal supports being arranged so that the grinding wheel axes swing along a path substantially diametrically of said frame, an independent motor on each of said supports for independently rotating said wheels, an independent nut and screw mechanism for adjusting each of said supports relative to said frame to feed said grinding wheels either toward or from the wire to be ground, a star wheel operatively connected to rotate each of said feed screws, and a pair of normally inoperative spaced plungers which are arranged to be moved into the path of movement of each of said star wheels at diametrically opposite positions to facilitate independent adjustment of each of said grinding wheels either toward or from the work axis.

CARL A. CARLSON.
